UNITED STATES PATENT OFFICE.

IVAR A. RANDEL, OF CHICAGO, ILLINOIS, ASSIGNOR TO McCORD AND COMPANY, OF CHICAGO, ILLINOIS, A CORPORATION OF NEW JERSEY.

DUST-GUARD WALL FOR JOURNAL-BOXES.

1,148,624.

Specification of Letters Patent.

Patented Aug. 3, 1915.

Application filed June 10, 1914. Serial No. 844,138.

To all whom it may concern:

Be it known that I, IVAR A. RANDEL, a citizen of the United States, residing at Chicago, in the county of Cook and State 5 of Illinois, have invented certain new and useful Improvements in Improved Dust-Guard Walls for Journal-Boxes; and I do hereby declare the following to be a full, clear, and exact description of the invention, 10 such as will enable others skilled in the art to which it appertains to make and use the same.

My present invention relates to journal boxes and is directed to the improvement of 15 the inside dust guard wall therefor. These inside dust guard walls are employed, for instance, in the journal boxes disclosed in my prior Patents 1,077,159, of date, October 28th, 1913, and 1,090,085, of date, March 10, 20 1914. In both of my said prior patents the inside dust guard walls were stamped from sheet metal, being formed independently of the pressed metallic cellars, and the tops of the boxes were cast onto the cellars and in- 25 side dust guard wall, after the latter had been properly positioned in the cellars. Hitherto, these inside dust guard walls have been stamped from sheet metal and given the approximately final contour in the 30 process of stamping or cutting from the metallic sheet; and this occasioned very considerable waste of sheet metal, due to the larger sizes of waste blanks.

My present invention effects a very great 35 saving in sheet metal and reduces the waste to a minimum, all as will hereinafter fully appear from the following detailed description.

In the accompanying drawings which 40 illustrate the invention, like characters indicate like parts throughout the several views.

Referring to the drawings: Figure 1 is a plan view showing in detail the complete 45 inside dust guard wall; Fig. 2 is a section taken on the line $x^2 x^2$ on Fig. 1; and Fig. 3 is a plan view showing the blank in the form from which it is stamped from the sheet metal.

50 Referring first to Fig. 3, the numeral 1 indicates the blank from which the inside dust guard wall is to be formed. This

blank, in this instance, is stamped or cut from a two and one-half inch wide sheet metal strip twenty seven inches long, which 55 has a total area of sixty seven and one-half square inches. The blank 1 is formed on one edge with end and intermediate projections 2 and 3, respectively, that are to be bent on the dotted lines y until they project 60 at a right angle to the face, or in other words, to the plane of the flat dimension of the strip. The strip or blank 1 is then bent (see arrows on Fig. 3) in the plane of its flat dimension until it is given the U shape 65 shown in Fig. 1. In thus bending the blank in the plane of its flat dimension, it will be held in a suitable frame or between suitable dies or plates which will prevent buckling 70 or kinking thereof, and cause the displacement of metal incident to the bending thereof, to take place entirely in the plane of the flat dimension of the said strip. Under this operation, the complete dust guard wall will have the metal in its intermediate and relatively wide portion displaced in the plane 75 of its flat dimension, that is, the metal on the outer curved edge thereof, will be stretched, while the metal on the other curved edge thereof, will be upset, more or 80 less. This completed inside dust guard wall is adapted to be inserted into the cellar of the journal box, and the laterally bent flanges 2 and 3 will then serve to hold the same properly spaced from the outside dust 85 guard wall of the box.

Here it may be stated that the dust guard wall shown is designed for application to a cellar having a rounded bottom, while in my prior patents above noted, the drawings 90 illustrate a cellar, the bottom of which is approximately flat at the point where the inside dust guard wall is applied. Otherwise stated, the inside dust guard wall illustrated in the drawings of the present application is designed for application to a slightly modified form of the cellar illustrated in my said prior patents.

In practice I have found that the improved dust guard wall above described, 100 made in accordance with my improved process, can be constructed from sheet metal with only approximately one-half the waste which has hitherto been necessary with the

old process wherein the dust guard wall has been directly stamped into an approximately final contour or outline.

What I claim is:

5. 1. A curved dust guard wall for a journal box made from sheet metal and having its intermediate portion displaced in the plane of its flat dimension.
10. 2. A U-shaped dust guard wall for a journal box made from sheet metal, having its

intermediate portion displaced in the plane of its flat dimension, and provided with end and intermediate flanges bent at an angle to the plane of said flat dimension.

In testimony whereof I affix my signature 15 in presence of two witnesses.

IVAR A. RANDEL.

Witnesses:

DONALD D. MILLIKIN,
F. D. MERCHANT.
